Primary Examiner — Mitchell I. Siegel(74) *Attorney, Agent, or Firm* — Michael J. Foycik, Jr.**(57) CLAIM**

The ornamental design for an bat, as shown and described.

DESCRIPTION

FIG. 1 is a top isometric view of an bat, showing my new design;

FIG. 2 is a bottom isometric view of the bat of FIG. 1;

FIG. 3 is a side view thereof, the bat being symmetric in all side views;

FIG. 4 is a top elevational view thereof; and,

FIG. 5 is a bottom view thereof.
